UNITED STATES PATENT OFFICE.

PEREZ M. STEWART, OF NEW YORK, N. Y., ASSIGNOR TO GERTRUDE F. STEWART, OF NEW YORK, N. Y.

COMPOSITE BEAM.

1,243,000.

Specification of Letters Patent. Patented Oct. 16, 1917.

Application filed March 4, 1916. Serial No. 82,228.

To all whom it may concern:

Be it known that I, PEREZ M. STEWART, a citizen of the United States, and a resident of the borough of Manhattan, in the city, 5 county, and State of New York, have invented an Improvement in Composite Beams, of which the following description, in connection with the accompanying drawings, is a specification, like characters on the 10 drawings representing like parts.

This invention relates to a portable composite bar, which is adapted among other uses to be employed in the construction of buildings, bridges and the like.

15 The invention has for its object to provide a portable composite bar, which is strong, light, and comparatively inexpensive and is capable of being made at the mill or on the job, and which is adapted for use as a beam, girder or other part of the building or other structure.

20 To this end, the composite bar is provided with substantially parallel side members and with a center or intermediate member of 25 plastic material, such as gypsum, concrete or the like.

The side members may and preferably will be made of metal bars or plates, which may be substantially thin and light, and which 30 are secured together in substantially close proximity to each other so as to be handled as one piece, by tie bars or rods, and are separated by suitable spacing devices.

35 The plastic material may, in some cases, be provided with a metal reinforcement, which extends lengthwise of the side members and through restraining devices, as will be described.

40 The side plates may be of any desired form or shape and may be made unflanged or provided with flanges as desired.

The plastic member may be extended below the lower edges of the side plates, for a purpose as will be described.

45 These and other features of this invention will be pointed out in the claims at the end of this specification.

Figure 1 is a cross section of a floor of 50 novel construction in which composite bars embodying this invention are used as beams and girders.

Fig. 2, an enlarged view with parts broken away of the floor construction shown in Fig. 1.

Fig. 3, a side elevation of the composite 55 bar shown in Fig. 1, and

Fig. 4, a plan view of the bar with the plastic member omitted.

Referring to the drawing and especially 60 Figs. 3 and 4, 10, 12, represent the side members of the composite bar, said members being shown as substantially thin metal bars or plates having outwardly extended bottom flanges 13, 14, but it will be understood that the plates or bars 10, 12, may be without 65 flanges or provided with flanges at their top and bottom.

The metal bars 10, 12, are arranged in 70 substantially close proximity to each other and may and preferably will be parallel, and they are connected together and secured in fixed relation at points in their length so as to be handled as one piece, by suitable devices, such as bars or tie rods or bolts 15, and are separated by spacing devices, preferably 75 metal sleeves 16 on said bolts.

The space between the side members 10, 12, is filled with plastic material 20, such as 80 gypsum, concrete and the like, which constitutes the intermediate or center non-metallic member of the composite bar, which will be hereinafter referred to as the plastic member of the said bar.

The plastic member may be strengthened 85 by a metal reinforcement of any suitable construction, but which is shown in the present instance as a metal rod 21, which is extended in the direction of the length of the bar and is passed under the intermediate tie rods or bolts 15 and may be extended 90 through and secured to restraining plates or devices 23, as represented in Figs. 3 and 4.

The plastic member when set adheres 95 firmly to the metal side members, and is bonded thereto, so as to form one rigid bar, which is capable of being handled as one piece and transported from the mill to the job, or which can be made on the job and handled as the ordinary steel girder, beam or bar. The plastic member when set serves 100 to stiffen and strengthen the side members, while permitting them to made thin, light and inexpensive.

The composite bars among other uses, are 105 especially adapted to be employed in the floor construction of buildings, and in Fig. 1, I have shown the same as used as beams, which are secured at their ends to girders 24,

or rest on angles or plates secured to the girders in the manner now practised with steel beams.

Referring to Fig. 1, the composite beams marked *a*, *b*, are secured at their ends to girders, only one 24 of which is shown.

The intermediate plastic members 20 of the beams *a*, *b*, are shown as extended below the bottom flanges 13, 14, of the side members 10, 12, and have bonded to them a layer 25 of plastic material, such as plaster, which forms a ceiling slab and is preferably keyed to the projecting portion 26 of the intermediate member 20 of the composite beams. In the present instance, the projecting end 26 of the intermediate member 20 is provided on its opposite sides with grooves 27, which are filled with ribs 28 on the ceiling slab 25. The layer 25 of plaster is supported by a layer 30 of metal, preferably wire mesh, which extends under the beams and is supported from the bottom flanges 13, 14, of the side members 10, 12, as by bolts or rods 31. The ceiling slab closes the bottom of the span between the beams, and above this slab is located a metal form or plate 33, which is preferably dome-shaped and corrugated and which may rest upon the bottom flanges 13, 14, or as herein shown upon the ceiling slab, upon which latter the metal dome 33 is placed after the ceiling slab has set sufficiently to sustain the said dome. The space above the metal dome 33 and between the latter and the side members of the composite beams is filled with a body or layer of concrete, gypsum or other plastic material, which forms a floor slab 36 and extends over the composite beams and is bonded to the plastic member 20 thereof, and said body or layer 36 is reinforced by metal tension members 38 extended under cross bars or rods 39 which may extend from girder to girder and be secured in fixed relation to the same, and which serve as deflecting members for the tension members 38 of the floor slab 36, which rests upon the metal dome 33. The tension members 38 may be placed under tension by securing one end to a composite beam by bending the end 40 of the said member over the beam and then passing them over the next adjacent composite beam and so on for the length of the tension members, and finally securing the opposite end of the latter to a composite beam.

The deflecting members 39 are placed upon the tension members and may and preferably will be used as supporting members for the metal form or dome, 33, for which purpose the metal dome may be suspended from the deflecting members by suitable tie-wires or eye-bolts 41.

In practice, the wire mesh 30 may be first secured to the flanges 13, 14, of the composite beams, and the plaster layer 25 is then

applied thereto to form the ceiling slab. When this slab has set sufficiently, the metal dome 33 is placed upon the same.

The tension members 38 are then placed in position and secured to the restraining plates or devices 23, and the deflecting members are then placed in position above the tension members. The concrete 36 is dumped or otherwise placed upon the metal dome and upon the flanges 13, 14, of the side members of the composite beams, with the result that a reinforced concrete building structure is obtained at a minimum expense, as the metal plates or bars thereof can be made thin and light, which not only reduces the cost of the metal structure but also reduces the weight to be sustained to such extent, that thinner and less expensive foundation walls and piers may be used, which lessens the cost of the building.

The dome is supported at its ends, and when the weight of the concrete is placed upon the dome, the latter is deflected at its center, and the deflection of the center of the dome causes the deflecting member to which it is tied to be moved sufficiently to place the tension member for the floor slab under permanent deflection and tension.

By providing the beams at their ends with the restraining plates or devices to which the tension member 21 is secured, the full compressive value of the concrete and the tensile strength of the steel reinforcement coordinate perfectly and in unison, and thereby develop the full value of each material in the beams.

While the composite bar is especially adapted for building constructions, it is not desired to limit the invention in this respect as the said composite bar can be used to advantage in other structures, as, for instance, in bridges and the like.

Claims:

1. A portable composite beam comprising metal side members arranged in substantially close proximity to each other, bolts extended through said side members between their ends to tie said members together, sleeves mounted on said bolts between said side members to space them apart, an intermediate member of plastic material bonded to said side members and movable therewith as a one-piece bar capable of being handled as such, and a metal reinforcement for said plastic member extended in the direction of the length of said side members under said bolts and in contact with said sleeves to be restrained thereby.

2. A portable composite beam comprising metal side members arranged in substantially close proximity to each other, bolts extended through said side members between their ends to tie said members together, sleeves mounted on said bolts between said side members to space them apart, an inter-

- mediate member of plastic material bonded to said side members and movable therewith as a one-piece bar capable of being handled as such, a reinforcing rod for said plastic member extended under said bolts in contact with said sleeves to be restrained thereby, and restraining plates at the ends of said side members to which said reinforcing rod is secured.
- 5 10. A portable composite beam comprising metal side members arranged in substantially close proximity to each other, devices for tying said side members together to be handled as one piece, end plates coöperating with said side members, a reinforcing rod extended under said tying devices and contacting therewith to be restrained thereby and secured at its ends to said end plates, and an intermediate member of plastic material bonded to said side members and enveloping said tying devices and reinforcing rod.
- 15 11. A portable composite beam comprising side members arranged in substantially close proximity to each other, devices for tying said side members together to be handled as one piece, an intermediate member of plastic material bonded to said side members and movable therewith as a one-piece beam capable of being handled as such, and a metal reinforcement for said plastic member extended in the direction of the length of said side members and coöperating with the said tying devices to be restrained thereby against upward movement.
- 20 12. A portable composite beam comprising side members arranged in substantially close proximity to each other, devices for tying said side members together to be handled as one piece, an intermediate member of plastic material bonded to said side members and movable therewith as a one-piece bar capable of being handled as such, and a metal reinforcement for said plastic member extended under said tying devices
- 25 5. The combination with composite beams provided with side members having flanges 50 at their lower portions, and an intermediate plastic member bonded to said side members and having a portion extended below said flanges, of a wire mesh located below said beams, means for securing said mesh to said 55 flanges, and a layer of plastic material supported by said mesh and bonded to the projecting portions of the plastic intermediate members of said beams.
6. The combination with composite beams 60 provided with side members arranged in substantially close proximity to each other, a device for tying said side members together to be handled as one piece and extended through the side members below the upper surfaces 65 of the latter, an intermediate member of plastic material between said side members and enveloping said tying device, and a metal reinforcement for said plastic member extended in the direction of the length 70 of said side members and coöperating with said tying device to be restrained thereby against upward movement.
7. A portable composite beam comprising side members, a sleeve interposed between 75 said side members and located below their upper surfaces, means extended through said side members for supporting said sleeve and tying said side members together, an intermediate member of plastic material between 80 said side members and enveloping said sleeve, and a metal reinforcement for said plastic material extended in the direction of the length of said side members and coöperating with said sleeve to be restrained 85 thereby against upward movement.
8. In testimony whereof, I have signed my name to this specification.

PEREZ M. STEWART.
